INVENTOR

Charles J. Van Depoele
By his Attorney

Frankland Jammes.

UNITED STATES PATENT OFFICE.

CHARLES J. VAN DEPOELE, OF CHICAGO, ILLINOIS.

ROOF FOR SUSPENDED ELECTRIC CONDUCTORS.

SPECIFICATION forming part of Letters Patent No. 367,475, dated August 2, 1887.

Application filed March 12, 1887. Serial No. 230,647. (No model.)

To all whom it may concern:

Be it known that I, CHARLES J. VAN DEPOELE, a citizen of the United States, residing at Chicago, in the county of Cook and State of Illinois, have invented certain new and useful Improvements in Roofs for Suspended Electric Conductors, of which the following is a specification, reference being had therein to the accompanying drawings.

10 The present invention relates to improvements in electric railways of the class in which a suspended conductor is used to carry the working-current to be supplied to the motors on the cars; and it consists in providing a continuous roof for said conductor, the object being to effectually protect it from accumulations of ice in cold weather, and also to protect the traveling contact when passing thereon.

15 In the accompanying drawings is shown an arrangement such as I have referred to, the particulars of construction and operation of which will be hereinafter pointed out.

20 Figure 1 is a view in perspective showing a portion of an electric railway, the suspended conductor of which is provided with a roof according to my invention. Fig. 1^a is a detail. Fig. 2 is a detail showing the construction of the frame of the roof, and Figs. 3 and 4 are slightly-modified forms thereof.

25 30 Similar letters denote like parts throughout.

35 A is the track. B B are poles for supporting a cross-wire or cable, C, from which is suspended by a suitable insulating hanger or support, D, the conductor E to be protected.

40 The roof F, which is located above the conductor is constructed of tarred canvas, paper, or any suitable fabric or material that has been treated with a waterproofing and preferably an insulating compound. The material, in the form of long continuous strips f, is prepared in any convenient manner and then packed in rolls ready for use.

45 The frame upon which the covering is supported may consist, as shown in Figs. 1 and 2, of a triangular board, G, secured to and resting upon the cross-wire C, and provided at its apex and bases with wires g, of iron or any other cheap metal, which are firmly secured 50 to the pieces G, located at each supporting-point, and extend continuously between said

supports and above the conductor E. Additional supports in the form of a light frame of iron or other material will be inserted at intervals between the main supports to keep the 55 wires g in proper relationship, and these additional pieces may be similar to the one G, or substantially as shown at G', Fig. 1^a.

60 In Fig. 3 is shown a slight modification of the foregoing, in which, instead of the roof being supported entirely above the cross-wires, wire-supports G' or boards G are secured to and depend from the insulator D, and the canvas covering is applied directly thereto.

65 In Fig. 4 the structure is slightly modified for use in connection with a particular form of insulator, D', which is in the form of a tube, from which one or more conductors are suspended by hangers e. In this instance, instead of a board G, I find it more convenient 70 to use a wire frame, as in Fig. 3, the top wire, g', being supported by an upright rod or stay, H, and the base-wires g², supporting the eaves of the roof, resting directly upon the tubular insulator, the central support, as well as the 75 wires g², preferably attached thereto by clips or bands h.

80 The supporting-wires g g' g² being in position along the line of the conductor E, the previously-prepared covering is unrolled and laid thereover, the lower edge being securely fastened by rivets, staples, stitches, &c., or by adhesion to the lower wires or eaves, and is then stretched longitudinally and also over the top wire on one side, the covering from the other 85 side being arranged to lap over that first applied, the edges or ends of the two sheets of material being united by hot tar, asphaltum, or any suitable cement.

85 90 In case of leaks, breaks, or injury to the covering a piece of new material coated with the protective substance or a suitable cement can be applied at any time, and in this manner repairs easily made.

95 I have suggested the use of two strips of material; but it will be obvious that I may use a single strip of sufficient width, and in that manner avoid the central lap, if found desirable; but the lapped joint has its advantages, 100 in that the most exposed portion of the line is in that manner provided with a double thickness of material.

Various modifications of the above-described construction will readily suggest themselves, and I therefore do not limit myself to the specific forms herein shown and described.

5 Having described my invention sufficiently for the purposes of this application, what I claim, and desire to secure by Letters Patent, is—

1. The combination, with a suspended conductor and cross-wires for supporting the same, of a continuous roof built upon and supported by the cross-wires from which the conductor is supported, substantially as shown and described.

15 2. The combination, with a suspended conductor, of a roof consisting of the supports G,

longitudinal wires mounted upon said supports, and the fabric placed over said wires, substantially as shown and described.

3. The combination, with a suspended conductor, of a continuous roof consisting of the supports upon the cross-wires, the longitudinal wires attached to said supports, the additional supports to keep the wires in proper relation, and the covering or fabric, all substantially as shown and described. 20 25

In testimony whereof I hereto affix my signature in presence of two witnesses.

CHARLES J. VAN DEPOELE.
